UNITED STATES PATENT OFFICE.

CALEB PAYNE, OF CHICAGO, ILLINOIS, ASSIGNOR TO GYPSUM ENGINEERING AND MANUFACTURING CO., A CORPORATION OF ILLINOIS.

MANUFACTURE OF BLOCKS.

Application filed August 14, 1922. Serial No. 581,660.

This invention relates to the manufacture of blocks from gypsum, stucco, plaster, cement, composition and the like, and has for its principal object to reduce the cost of manufacture and improve the quality of the product.

A further object of the invention is to produce an improved process by which the abuse of the blocks heretofore incident to withdrawing the cores is eliminated; by which a denser, heavier mixture can be used; by which perfect formation of the blocks is assured; by which a balanced block of uniform cross-section is produced; by which the cores are maintained in a clean, lubricated condition and adhesion of the mixture thereto is prevented and by which the use of cores having uniform cross-section is made possible.

20 A further object of the invention is to produce a simple and efficient machine for making blocks according to the new process, and in which a plurality of molds are moved in a circuit and the operations of forming 25 and discharging the blocks are performed at regular points in the circuit.

A further object of the invention is to provide a mold in which the cores are inserted and withdrawn through a lubricating 30 and cleaning medium.

Further objects of the invention will become apparent as the disclosure proceeds, and the description is read in connection with the accompanying drawing showing a 35 selected embodiment of the invention in which

Fig. 1 is a plan view of the machine,

Fig. 2 is a section taken on the line 2—2 of Fig. 1;

40 Fig. 3 is a section taken on the line 3—3 of Fig. 1;

Fig. 4 is a perspective view of one form of block;

45 Fig. 5 is a perspective view of one arrangement of cores and partitions;

Fig. 6 is a section taken on line 6—6 of Fig. 2, and

50 Figs. 7, 8, 9 and 10 are sections taken on the line 7—7 of Fig. 6, certain mechanism for withdrawing cores from the molds being shown in a plurality of positions.

The drawings are somewhat diagrammatic and a great deal of detail has been omitted in order to eliminate confusion and

make the illustration clearly depict the cardinal features of the invention.

55 The machine illustrated is particularly designed for the manufacture of blocks from gypsum and will be described accordingly, but it will be understood that the use of the term "gypsum" is for convenience in description and is not intended to limit either the process or the machine to use with that material, for the principles of the invention readily lend themselves to the manufacture 60 of blocks from a great variety of materials, which can be molded while in a fluid or plastic condition and will harden with the lapse of time.

65 Referring to the drawings, the reference numerals 10 and 11 (Fig. 2) indicate rails of a circuitous track. Ordinarily it will be convenient to make this circuit circular, but under some conditions, other forms will be more suitable. The rails 10 and 11 receive 70 wheels 12 and 13, which support side frames 14 and 15, which in turn carry a superstructure consisting of concentric channels 16 and 17 secured in spaced relation by the spacers 18 (Fig. 3). Each spacer is in the form of 75 a rectangular frame open at its top and bottom equipped at its inner end with the back 19 of a mold and in the present embodiment the several backs are rigidly secured to the spacers and held permanently 80 in an upright position by means of bolts 20 passing through flanges 21 and clamping them to spacers. Upright rods 22 are mounted in the inner ends of each spacer and the inner channel 17 and side pieces 23 85 of the molds are hinged thereon. The outer end of each spacer is equipped with a hinge 24 on which is mounted front 25 of the mold.

90 A gear 26 is suitably mounted on and disposed concentrically with the frame composed of the channels and spacers and is driven by a pinion 27 receiving power from a motor 28 through reduction gearing 29. This will cause the molds to move in the circuit. The 95 pinion 27 is provided with a blank or mutilated section 30 which will permit the molds to come to rest and remain stationary for a suitable period and then automatically move along the circuit again. In other 100 words, the travel of the molds will be intermittent or step by step with pauses of suitable length between the movements.

Each mold is open at its top and closed by a bottom member 31 supported upon the top of the rectangular spacer 18 to which it is secured in any suitable manner. In the present illustration the mold bottoms are made hollow and filled with absorbent material 31^a, which is supplied with oil from a tank 32 through pipes or the like 33 equipped with valves 34. The tank 32 is supported on a frame 35, which is made principally of braces secured to the backs 19 of the molds. Figure 5 of the drawings shows the mold bottom 31 in the form of a rectangular box, and the oil inlet thereof is shown at 31^b.

Any suitable number of cores may be used and partitions may be inserted in the molds to divide them into any suitable number of sections. In the machine illustrated I use three partitions and twenty cores which enable me to make four blocks in one mold and provides five passages in each block. The cores and partitions are carried by suitable heads 36 which reciprocate between the positions shown at the left and at the right in Fig. 2. The cores 37 are preferably of uniform cross-section and made of metal, and the partitions 38 are preferably of rigid sheet metal. The mold bottoms 31 with their oil soaked absorbent material 31^a form stuffing boxes through which the cores and partitions are inserted into and withdrawn from the molds and they are thereby kept lubricated.

According to the preferred procedure, the gypsum or other material in a fluid state is charged into the molds at a suitable point in the circuit, the cores and partitions are inserted and remain until the material is no longer fluid, when they are withdrawn, the mold opened and the block discharged. Preferably the cores are withdrawn from the charge shortly after it ceases to be fluid but the exact time will depend upon particular conditions. It is important that the withdrawal take place before the gypsum adheres to the cores, which occurs as the block becomes set, or as the material changes from a plastic condition to a firm condition.

The machine is adapted to automatically insert cores at one point in the circuit, withdraw them at another point, open the molds at another point and discharge the blocks at another point. Cores and partitions carried by a head 36 are supplied for each mold and suitably mounted so as to remain in either inserted or withdrawn position, as shown in Fig. 2. The heads 36 are equipped with under cut jaws 40 adapted to receive plates 41 and 42 carried by racks 43 and 44. The rack 43 inserts cores and the rack 44 withdraws them. Preferably these actions are simultaneous in that the cores are inserted in one mold at the same time that the cores are withdrawn from another mold. To

accomplish this I provide a shaft 45 equipped with pinions 46 and 47 engaging with the respective racks 43 and 44 on opposite sides thereof. A pinion 49 on shaft 45 meshes with a gear 50 on a jack shaft 51 supported in a suitable frame 52 and equipped with bevel gears 53 and 54 loosely mounted thereon. These gears mesh with a bevel gear 55 on a shaft 56 (Fig. 1) which is driven by a motor 57 through suitable reduction gearing 58. The clutch 59 on the shaft 51 may be thrown by lever 60 to engage either of the gears 53 or 54 with the shaft 51 or to occupy a neutral position in which both gears are permitted to idle on the shaft.

By providing means for throwing this clutch at the proper time and by locating the shaft 45 and racks 43 and 44 in the proper relation to the circuit the cores will all be inserted at a predetermined point and will all be withdrawn at another predetermined point. This can be accomplished in a great variety of ways and I have shown a simple cam and lever arrangement to illustrate how it can be worked out. The bell-crank lever 61 is pivoted at 62 and has one arm 63 connected by a link 64 with the lever 60. Another arm 65 of this bell-crank lever lies in the path of strikers 66 and 67.

Bell-crank 61 being in neutral position with respect to the clutch 59, just as the molds come to a pause a cam surface 68^a (see Fig. 6) of the cam 68, carried by the side frame 15 throws the lever 63 to the left so as to engage the clutch 59 and causes the rack 43 to ascend and the rack 44 to descend while the molds are stationary.

As shown in Figs. 7 and 8 the rack 44 travels downwardly until the striker 67 engages the arm 65 of a bell-crank lever 61 and restores the clutch to neutral position. When the machine is moved sufficiently to disengage the jaws 40 of these molds from the plates 41 and 42, another cam surface 68^b (see Fig. 6) of the cam 68 will shift the lever 63 to the right and engage the clutch 59 so as to raise the rack 44 and lower rack 43 to positions wherein the plates 41 and 42 may be received by jaws 40 of the next molds that come to inserting and withdrawing positions. (Fig. 9.) The upward movement of the rack 44 is limited by the striker 66 which engages the lever arm 65 and restores the clutch to neutral position, as shown in Fig. 10. As the machine comes to rest at the next pause the cam surface 68^a of the cam 68 will again move the lever 61 to engage the clutch 59 with the proper gear to cause the cores to be inserted in one mold and withdrawn from another.

Each set of cores, in its lowered position, is supported upon the rails 95 on which they travel from the station where the cores are withdrawn to the station where the cores are inserted into the mold.

The cores are inserted during the pause immediately following that in which a charge is put into the molds as indicated at the top of Fig. 1 and the cores are withdrawn at some suitable point thereafter, depending upon the particular material that is being used. At a suitable time after the cores are withdrawn the molds are opened and the blocks are discharged.

- 10 The sides 23 of the molds are provided with arms 70 which engage the cam 71 that serves to open the sides against the resistance of springs 72 (Fig. 3) and remove the flanges 74 thereof from the edges of the front 25. 70
- 15 Each front 25 is equipped with a counter-weighted arm 75 that holds it normally in closed upright position. However, by tilting the block the counterweight can be raised and the front with block lowered onto 80
- 20 a table or belt, such as illustrated by 77 in Fig. 3. Preferably a shock absorber 78 is arranged to receive the front 25 and also to permit it to descend to the point illustrated in dotted lines in Fig. 3 without dangerous 85
- 25 shock. As soon as the block leaves the front 25 the counterweighted arm will move it back into normal position; and, when the arms 70 pass beyond the end cam 71, the sides 23 close on the front and the mold is 90
- 30 ready for the next charge.

The blocks may be discharged by the means illustrated particularly in Fig. 3. A foot 80 shaped to fit any one of the core openings is carried by a resiliently mounted 95

35 shank 81 which moves in a socket 82 carried by a reciprocating rod 83 that moves in the guides 84 on the inclined frame 85. An arm 86 on shank 81 engages the cam 87 on the back of each mold which raises the foot and 100

40 allows it to descend at the proper time to enter one of the core openings. The rod 83 is equipped with rack 88 that engages a mutilated pinion 89 on the shaft 90, which is driven by shaft 91 through bevel gears 92. 105

45 Shaft 91 is equipped with gear 93 meshing with gear 26. The arrangement is such that as the machine approaches the position where block is to be discharged the mutilated pinion 89 engages the rack 88 and 110

50 tilts the block so that it descends to the dotted line position shown in Fig. 3 and at the proper time to slide on to the belt 77. The inclined position of the bar 83 causes the foot 80 to automatically free itself when 115

55 the block has been tilted sufficiently to cause it to descend against the resistance of the counterweighted arm 75. At about this point the mutilated portion of the pinion 89 comes opposite to the rack 88 and the 120

60 spring 94 returns the rack to normal position.

In order to make the block pivot about the axis of the front portion of the mold and to prevent it from sliding inwardly 125

5 along the bottom of the mold the inside face

of the front portion 25 is provided with beveled lugs 95 having their inner faces at right angles to the bottom of the block and forming stirrups to carry the blocks until the front portion 25 takes the position in which it acts like a chute. The bottom of the mold is equipped with recesses 96 (Fig. 5) to receive these lugs when the front portion is in closed position.

In the normal operation of the machine 75 the motor 28 is started and the molds travel by intermittent movement that permits proper pauses during which the cores are inserted and withdrawn and the blocks are discharged from the mold. When a mold approaches the charging position indicated at the upper left hand side of Fig. 1 a suitable quantity of the block mixture is introduced through the open top of the mold by any preferred means. At the next pause the cores 37 and partitions 38 are inserted into the mold and through the mixture. Any excess of block material is then struck off preferably into the following mold which at that time is in charging position. The charged mold with its cores in place then travels through the intermittent steps until the block material is no longer fluid which brings it to a position indicated at the lower right hand portion of Fig. 1 where the cores are withdrawn. In the preferred form of the machine the inserting of one set of cores and the withdrawal of another set of cores takes place simultaneously, and immediately after this action the machine is in the condition illustrated in the somewhat distorted drawing shown in Fig. 2. After the cores are withdrawn the mold with its formed block travels on in the circuit until the block material has set sufficiently to permit the block to be handled without danger. It is then that the arms 70 on the side members of the mold come in contact with the cam 71 causing the sides to be opened; and as the mold approaches the table or belt 77 the foot 80 engages the block and tilts it until its center of gravity is beyond the axis of the hinge 24 when the weight of the block will cause both the block and the front portion of the mold to descend into the dotted line position shown in Fig. 3, when the block slides on to the belt 77 and the front portion of the material automatically returns to normal position in time to be caught by the flanges 74 on the side members as 130

The time necessary for the block material to pass beyond the fluid state will vary with different materials and that gypsum will depend upon the presence or absence of a retarder as well understood in the art. The distance between the inserting jack and the withdrawing jack will be made sufficient to take care of average conditions and if an extraordinary period is required the adjust-

ment can be made by changing the speed of the molds. It is an important feature of the invention, however, that the cores and partitions, if any are used, be inserted 5 while the block material is fluid and be withdrawn after the block material has ceased to be fluid but before it adheres to the cores and the partitions. As a general thing it will be preferable to withdraw the cores and 10 partitions while there is still free liquid next to them because that permits the withdrawal to take place with a minimum of friction and consequently a minimum of abuse of the delicate blocks. This condition ceases 15 as the block material becomes set and at that time adhesion begins to take place. It is this adhesion that has heretofore been the chief cause of the troubles experienced in withdrawing cores. As a general thing the material will allow considerable latitude in the 20 time of withdrawing the cores and partitions because it will cease to be fluid some little time before adhesion takes place or the free liquid disappears. There is some advantage 25 in withdrawing the cores and partitions while the material is plastic for while it is in that condition a certain amount of movement during the withdrawal would not cause any incipient cracks or otherwise reduce the strength of the block.

Block molding material has what is known as the initial set and the final set. The initial set is the amount of time which must elapse before the mixture becomes a hydrate 30 and there is no longer any free water in the mixture, while the final set is the amount of time which must elapse for the material to become sufficiently set or hard to enable the discharge of the block from the mold. The 35 periods of initial set and final set may be obtained from the manufacturers of the block material, or may be obtained by laboratory tests. If the time period for an initial set is three minutes, the cores of the present machine would be withdrawn from the mold about thirty seconds before the initial set 40 takes place, thereby to insure that the block material immediately surrounding the cores is in a fluid condition. Where the time of 45 the initial set is three minutes, the time for the final set would be about eight minutes. With this understanding of initial set and final set, it will be explained that the station for withdrawing the cores is located, with 50 respect to the charging station, that each charged mold will reach the core withdrawing station just prior to the point of initial set, in order that the cores may be withdrawn while the block material is in a fluid 55 condition next to the core, and the block discharging station is located with respect to the core withdrawing station so that the mold, with the cores withdrawn therefrom 60 will reach the discharging station at about 65 the termination of the final set in order that

the block may be discharged from the mold without damage to the block.

By inserting the cores and partitions into a charge of fluid block material it becomes possible to uniformly distribute the material from one end of the block to the other eliminating all voids and all tendency of any aggregate, such as shavings or hair, to collect at one side of the core or cores. By pushing the cores and partitions up from the bottom 70 they can be put through a very light aggregate without destroying the uniformity of the mixture. This procedure also permits blocks to be successfully molded in upright 75 position which has heretofore proved impractical.

The reason that it has been impracticable heretofore to mold blocks in vertical molds is that it was the practice to have the cores in place during the pouring of the mixture 80 into the mold, and under these conditions the mixture has a tendency to form air locks or pockets, and the material would not always reach the bottom of the mold. Attempts 85 have been made to overcome this fault by the use of a light mixture, but the fibers or other light aggregate in the mixture will float to the upper portion of the mold, thus producing a block which in the upper portion would 90 be of one strength and in the lower portion 95 of another strength. This objection still exists in blocks made in horizontal molds with the cores in place, because of the tendency of the mixture to form air locks or pockets as it flows into place beneath the 100 cores which are horizontally disposed in the molds.

The insertion of the cores and partitions through a lubricating medium and withdrawing them through such a medium is 105 of the greatest practical importance because it automatically cleans and lubricates them. When a core or partition is withdrawn through the oil box or the like any block material collected on its surface is removed 110 and a thin layer of lubricant is laid on the cleaned surface. When the core or partition is again inserted any block material that has collected adjacent to the entrance to the mold will come in contact with the lubricated surface to which it cannot stick. This feature of the invention practically eliminates the serious difficulties heretofore experienced with cores and has the further advantage of permitting cores of uniform 115 cross-section to be used, which in so far as I am aware has never been found feasible. The use of such cores is of great advantage because it permits the blocks to be made of uniform weight or cross-section of area from 120 end to end which form of block is not only more satisfactory in use but there is a saving of material.

In the manufacture of blocks from gypsum lubricating oil will be found the most satis- 125

factory lubricant but with some materials other oils will be preferred and it is contemplated that water may be used for this purpose. Consequently, in using the term 5 "lubricant" I intend to define the broad function.

In the illustration the cores are arranged for the manufacture of three inch blocks, but if it is desired to make four inch blocks, the 10 same cores could be turned through ninety degree and a greater number used while leaving the necessary thickness of side walls. The use of rectangular cores of uniform 15 cross-section also has the advantage that in changing the width of a block it is possible to rearrange the cores and save material which would be lost in the usual practice with tapered cores of circular cross section.

20 In certain work it will be found convenient to charge the mold with material in a plastic condition, in which case the cores can be withdrawn immediately after they are inserted. Two sets of cores moving in 25 opposite directions have some advantages when a plastic charge is being formed.

I claim:

1. The process of making cored blocks, which consists in taking an open topped 30 mold, pouring block material in a fluid condition into the mold through the open top thereof, then thrusting a core endwise into the fluid material in the mold while the top of the mold is open, and then withdrawing 35 the core after the material has ceased to be fluid and before the initial set thereof has taken place and while the material is confined within the mold.

2. The process of making cored blocks 40 which consists in taking an open topped mold, pouring block material in a fluid condition into the mold through the open top thereof, then thrusting a core endwise and upwardly through the bottom of the mold 45 and into the fluid material therein while the top of the mold is open, and then withdrawing the core downwardly after the material has ceased to be fluid and before the initial set thereof has taken place and while the material is confined within the mold.

50 3. The process of making cored blocks, which consists in taking an open topped mold, pouring block material in a fluid condition into the mold through the open 55 top thereof, then thrusting a core endwise into the fluid material in the mold while the top of the mold is open and then withdrawing the core after the material has ceased to be fluid and before the initial set thereof has taken place and while the material is confined within the mold, subsequently opening the mold, and then discharging the molded block.

4. The process of making cored blocks 60 which consists in taking an open topped

mold, pouring block material in a fluid condition into the mold through the open top thereof, then thrusting a core endwise and upwardly through the bottom of the mold and into the fluid material therein while the 70 top of the mold is open, and then withdrawing the core downwardly after the material has ceased to be fluid and before the initial set thereof has taken place and while the material is confined within the mold, subsequently opening the mold, and then discharging the molded block.

5. In a machine for making blocks, the combination of a plurality of molds adapted 80 to travel in a circuit, means for moving the molds intermittently, means for inserting and withdrawing cores while the molds are at rest, means for opening the molds while they are in motion, and means for discharging the blocks therefrom.

6. In a machine for making blocks, the combination of a mold, a lubricator adjacent thereto, means for moving the mold, a core 90 slidable through said lubricator into and out of said mold while the latter is at rest, and means for opening the mold while it is in motion.

7. In a machine for making blocks, the combination of a mold, a lubricator adjacent thereto, means for moving the mold, a core 95 slidably mounted in said lubricator, and means for moving said core into and out of said mold while the latter is at rest and means for opening the mold while it is in motion.

8. In a machine for making blocks, the combination of a mold having a lubricator at the bottom thereof, means for moving the mold, a core slidably mounted in said lubricator, and means for inserting and withdrawing the core through said lubricator and means for opening the mold while it is in motion.

9. In a machine for making cored blocks, the combination of a plurality of molds 110 adapted to move in a circuit, each mold having a lubricator, a core slidably mounted in said lubricator while the mold is at rest, means for opening the molds while they are in motion, and means for supplying lubricant to all of said lubricators.

10. In a machine for making cored blocks, the combination of a plurality of upright molds, means for moving said molds, a lubricator at the bottom of each mold, a core 120 slidably mounted in each lubricator while the molds are at rest, means for opening the molds while they are in motion, a tank for lubricant, and passages connected to said tank with each of said lubricators.

11. In a machine for making blocks, the combination of a plurality of molds adapted to travel in a circuit, means for intermittently moving said molds about the circuit, means for inserting a core in each mold dur- 130

ing a pause between intermittent movements, means for withdrawing the core from each mold during another pause, means for opening the molds during a period of movement, and means for discharging the blocks from the molds.

12. In a machine for making blocks, the combination of a plurality of molds adapted to move in a circuit, a jack occupying a relatively fixed position in the circuit and adapted to insert a core in each mold, a second jack located at a relatively fixed point in a circuit and adapted to withdraw the core from each mold, and means for automatically starting and stopping the operation of the jacks.

13. In a machine for making blocks, the combination of a plurality of molds adapted to travel in a circuit, means for moving said molds about said circuit intermittently, a core moving with each mold, a jack located at a relatively fixed point in the circuit and adapted to engage each core and insert it in each mold, another jack located at a different point in the circuit and adapted to engage each core and withdraw it from its mold, and means for automatically starting and stopping the operation of the jacks during the periods when the molds are at rest.

14. In a machine for making blocks, the combination of a plurality of molds adapted to travel in a circuit, means for moving the molds intermittently about the circuit, a core travelling with each mold, jacks located at relatively fixed points in the circuit, and means for automatically and simultaneously operating said jacks to insert a core in one mold and withdraw a core from another mold.

15. In a machine for making blocks, the combination of a plurality of molds adapted to move in a circuit, a core moving with each mold, means for moving the cores and molds about the circuit, jacks for inserting the cores and withdrawing them, and means controlled by the moving cores for operating said jacks.

16. In a machine for making blocks, the combination of a plurality of molds adapted to move in a circuit, a core adapted to move with each mold, core inserting means and core withdrawing means located at adjacent points in the circuit, and means controlled by the movement of the core for operating said inserting and withdrawing means.

17. In a machine for making blocks, the combination of a frame adapted to travel in a circuit, a plurality of molds carried by said frame, a core carried by said frame for each mold, a jack located at a relatively fixed point in the circuit and adapted to insert each core in its mold, another jack located at another point in the circuit and adapted to withdraw each core from each mold, and means controlled by the movement of the frame for operating said jacks.

18. In a machine for making blocks, the combination of an endless guideway, a series of molds mounted to travel along the guideway, means for charging fluid block material into the molds, means for inserting cores into the fluid material in the molds subsequent to the charging thereof, means for withdrawing the cores, means for opening the molds after withdrawing the cores, means for discharging blocks from the open molds, and means for closing the molds.

CALEB PAYNE.
